United States Patent Office.

JOHN W. POST, OF CASTILE, NEW YORK.

Letters Patent No. 74,421, dated February 11, 1868.

IMPROVEMENT IN SKATES.

The Schedule referred to in these Letters Patent and making part of the same.

TO ALL WHOM IT MAY CONCERN:

Be it known that I, JOHN W. POST, of Castile, in the county of Wyoming, and State of New York, have invented a new and useful Improvement in Skates; and I do hereby declare the following to be a full and correct description of the same, sufficient to enable others skilled in the art to which my invention appertains to fully understand and use the same, reference being had to the accompanying drawings, which make part of this specification, and in which—

Figure 1, sheet 1, is a side elevation of my improved skate, and

Figures 2, 3, 4, 5, 6, sheet 1, and 7, 8, 9, 10, 11, 12, 13, 14, 15, sheet 2, are detached views of parts of the same, as hereinafter more fully described and referred to.

Like letters of reference indicate like parts in the several figures.

The nature of my invention consists in the peculiar construction of a skate, so that by the use of one lever only the same may be attached instantaneously to the foot, without straps, and without the necessity of any plate or other contrivance in the heel, or any other part of the boot, to assist in holding the skate to the foot.

A, in the drawings, represents a skate-runner, having three elevations or standards, B, C, and D, cast or otherwise formed in one piece with the runner. Straddling the standard B, and attached to it by a screw, a , is a bracket or support, E, provided with a slot, e , and two flanges, b and c , which latter are provided with holes, b^1 c^1 , into which screws b^2 c^2 fit, by means of which the heel-plate G is secured on the bracket E. The slot e , in the bracket E, has a cross-slot, e' , in which the shoulder f of the screw F has its bearing. This screw has a smooth stem, f' , its threaded part working in a sleeve, d , provided with a projection, d' , which projects through a slot, g , in the heel-plate, and which forms a bearing for the forked lever G'. This lever G' has a serrated or toothed pivoted end, g^1 , the other end being bent, as shown at g^2 . Attached to the standards C and D is the foot-plate H, which, in its rear part, has a slot, h , into which the bent end g^2 of the lever G' fits. The foot-plate H is secured to the standard C by means of the bracket I, constructed similarly to the bracket E, with a single difference. Instead of the upper edge of the standard C being cut out as that of the standard B, (see fig. 6,) it is cut out in V-shape, (see fig. 15,) the inner face of the straddling-bracket I being shaped to correspond to the V-shaped cut. By this arrangement, the foot-plate H is not only supported by the bracket I, but also rests on the edges i of the standard C—a very important result, as it is very necessary, in skates of this kind, to have the foot-plate immovable on the standard.

Fig. 12 is an end view of the standard C, bracket I, and the foot-plate H, when the standard is shaped as in fig. 6, and the foot-plate rests on the bracket alone. Fig. 14 is a vertical cross-section in line x x , fig. 13, and shows the point of the angle of the V-shaped cut at i .

Fig. 7 is a top view of the foot-plate H, which is provided with two slots, K. These slots have a part of their rear edges serrated, the remainder of their edges being perfectly smooth. L, figs. 8 and 9, represent clamp-plates, which slide under the foot-plate, and are secured to the same by means of a set-screw, l , passing through the slots K, downward into the hole l' of the clamp L.

K is a spur, pointed at the rear, and flat at the front side, formed on the inner edge of the clamp L, and as long as the slot K is wide across the serrations. This spur fits into the serrated slot K, securely holding the clamp, its point passing into one of the serrations in the slot. By this means the clamp-plate cannot move sideways, and when it is desired to shift the clamp, the screw l need only be loosened sufficiently to allow the spur K to be shifted into another serration, when, by tightening the screw l , the clamp is again securely and firmly held in place.

In figs. 10 and 11, a modification of the lever-device is shown. In this modification, the projection d' on the sleeve d is a pin, and forms the pivot for the lever G', provided with a hole, g^3 , which passes over the pin d' . The lever has a cam-shaped rear elevation, m , provided with grooves, n , which form semicircular cutting-edges, o , which, when the lever is turned in line with the foot, seize into and securely hold the heel of the boot, as shown in fig. 10. The lever is secured to the foot-plate in the manner already described. The clamps L need be set to the boot but once, as they will fit then always.

To attach the heel by the lever G', as shown in fig. 1, the lever is lifted from the slot h into the position shown in red lines. The front part of the foot being between the clamps L, the heel is put down between the

brackets *p*, formed on the heel-plate *G*, and the lever *G'* raised into position, as shown in black in fig. 1. This movement has two results. The lever *G'*, moving on a pivot, has a circular motion, so that by forcing the teeth into the inner side of the heel, the latter is not only pressed back against the brackets *p*, but also downwards on to the heel-plate *G*, thus forming a firm and secure fastening. When the lever *G*, shown in fig. 10, is used, the cam-shaped end of the same forces the heel back against the brackets *p*, the edges *o* seizing into and securely holding the heel. After or before the lever *G'* is secured, the same may be set to any size heel by means of the screw *F*, which moves the sleeves *d*, bearing the lever either forward or back, as desired. In this skate-fastening there is nothing to be done to the boot; no hole bored into the heel, no plate to be let into the same, and the skate can be put on and fastened in one moment.

Having thus described my invention, what I claim as new therein, and desire to secure by Letters Patent, is—

1. The heel-fastening, consisting of the lever, pivoted on a sleeve, *d*, and made adjustable by means of the set-screw *F*, substantially as described.
2. The pivoted lever *G*, having a serrated rear face, and secured to the foot-plate *H*, substantially as set forth.
3. The device for adjusting the pivoted lever *G'*, consisting of the sleeve *d*, moved by the set-screw *F*, provided with a shoulder, *f*, which has its bearings in the cross-slot of the slot *e*, in the bracket *E*; substantially as described.
4. The clamps *L*, provided with spurs *k*, in combination with the partly-serrated slots *K*, substantially as and for the purposes described.
5. The V-shaped cut *i* in the standard *C*, and the correspondingly-shaped bracket *I*, substantially as and for the purposes set forth.

The above specification of my improvement in skates signed, this twenty-second day of January, 1868.

JOHN W. POST.
